UNITED STATES PATENT OFFICE

ANNA L. CROCKER, OF CHICAGO, ILLINOIS

STOCKING PROTECTOR

Application filed March 18, 1929. Serial No. 347,927.

The present invention relates generally to stocking protectors. More particularly the invention relates to those protectors which are formed of waterproof material and are adapted, during wet and rainy weather, to be worn around the ankle portions to protect the underlying parts of the wearer's stockings from being soiled with mud and water that may be splashed by passing pedes-
10 trians or vehicles.

One object of the invention is to provide a protector of this character which is formed of inelastic material, such, for example, as rubberized silk, and is capable of being slipped readily over the foot and shoe and then fastened in place so as to extend around and conform substantially to the ankle portion and encompass the contiguous parts of the stocking. In general this protector is in
20 the form of a circumferentially continuous tube which is of sufficient width to permit the foot and shoe of the wearer to be passed readily therethrough and withdrawn without inconvenience or difficulty. When the
25 protector is in its operative position, the side of the so called tube is doubled back or folded in so as to take up the excess material and cause the protector to fit closely about the ankle of the user.

Another object of the invention is the provision of improved and properly positioned means for holding the protector in place, which includes a vertically arranged or positioned stay operating to prevent the protector from wrinkling and collapsing around the shoe.

A further object of the invention is to provide a stocking protector for use in inclement weather, which while affording warmth and protection to the leg is neat and attractive in appearance.

A still further object of the invention is to provide a stocking protector which may be manufactured or produced at a low reasonable cost and is generally an improvement, as far as construction and application are concerned, over previously proposed protectors of this type.

Other objects of the invention and the various advantages and characteristics of the

present construction will be apparent from a consideration of the following detailed description.

The invention consists in the several novel features which are hereinafter set forth and are more particularly defined by the claim at the conclusion hereof.

In the drawings which accompany and form a part of this specification or disclosure and in which like numerals of reference denote corresponding parts throughout the several views:

Figure 1 is a side elevational view of a stocking protector embodying the invention, showing the same in its unfolded or inoperative position, in which position of the protector the foot and shoe of the user may be inserted readily and quickly therethrough and withdrawn;

Figure 2 is a plan view, partly in section, illustrating in detail the tubular conformation of the protector and the manner in which the stay is held and secured in place;

Figure 3 is a side elevation, showing the protector in its operative and folded position circumventing and protecting the ankle portion of the wearer's stocking; and

Figure 4 is a plan view, illustrating the manner in which one side of the protector is folded or doubled in so as to cause the protector to conform to and fit closely about the ankle.

The invention is exemplified in a stocking protector which comprises a pair of side pieces 5 and 6. These pieces are formed of any suitable inelastic material, such, for example, as rubberized silk. The piece 5 is adapted to cover one side of the wearer's leg and to extend from the upper parts of the shoe to a point intermediate the ankle and calf. The side piece 6 is coextensive with the piece 5 as far as height is concerned, and is adapted to cover the other side of the wearer's leg. The front side margins of the two pieces are connected together from top to bottom by a strip 7 of tape, and stitching 8. The rear side margins of the two pieces are similarly connected together from top to bottom by a tape strip 9 and stitching 10. Tapes 11 and 12 are secured respectively to the top and bottom

margins of the protector so that the edges cannot be torn readily and for reenforcing purposes. These tapes are bent around the edges of the side pieces so as to be of U-shaped cross 5 section and are secured in place by stitching. By securing the side margins together in the manner set forth, the protector is in the form of a circumferentially continuous tube. The back portion of the side piece 6 embodies considerably more material than the back portion 10 of the side piece 5 so that the width of the protector is materially greater than the ankle of the wearer. As a result of this arrangement or construction, the wearer's foot and shoe may be readily inserted into and 15 withdrawn from the protector without inconvenience or difficulty, as indicated by dotted lines in Figure 1 of the drawings. The lower front portions of the side pieces 5 and 6 are extended frontwardly so as to lap and cover the instep when the protector is in its operative position. The bottom marginal parts of the pieces 5 and 6 are adapted to fit over the upper parts of the shoe to prevent the entry 20 of water or mud. After the protector has been shifted into position around the ankle portion of the wearer's leg, the rear portion of the side piece 6 is doubled back or folded in, as illustrated in Figures 3 and 4, so as to 25 cause the protector to be contracted and fit snugly around and conform substantially to the ankle and associated parts.

When the protector is in its operative and folded position it is held in place by a pair 30 of straps 14, a pair of straps 15 and a pair of straps 16. The straps 14 are positioned adjacent the top of the protector. One of these straps has one end thereof connected to the front side margins of the pieces 5 and 6 directly beneath the strap 11 by the stitching 8. One end of the other strap 14 is connected to the rear side margins of the side pieces by the stitching 10. The free ends of said straps 14 are adapted to extend around the side piece 6 and be tied together, as shown in Figures 3 40 and 4, to hold the folded part in place. The straps 15 are positioned adjacent the central portion of the protector and are secured in place by the stitching 7 and 10 similarly to the straps 14. The straps 15 are adapted to extend around the side piece 6 and to be tied together to hold the central portion of the protector in place. The straps 16 are located 50 at the lower end of the protector. One end of one of the straps 16 is secured to the rear margins of the side pieces by the stitching 10 and is located directly above the tape 12. The other strap 16 has one end thereof secured to the lower central portion of the side 55 piece 6. When the free ends of the straps 16 are tied together, they hold in place the lower end of the protector. The lower front portions of the side pieces 5 and 6 which are adapted to extend over the instep are held in place by an elastic strap 17. This strap is

adapted to extend under the arched portion of the sole of the shoe directly in front of the heel and has the ends thereof sewed or otherwise suitably secured to the tape 12.

To prevent wrinkling of the protector a stay or stiffened member 18 is provided. This stay is contained or housed within a vertically elongated pocket 19 adjacent the central portion of the side piece 6. The pocket 19 is formed by folding the central portion of the piece 6 into the form of a small loop and stitching the folded portion as at 20. The pocket, as well as the stay, extends from the bottom tape 12 to the top tape 11.

In applying the protector, the wearer first opens it up and then inserts the foot and shoe therethrough (see Figure 1). During this step the toe of the shoe is positioned under the instep portion of the pieces 5 and 6 and in front of and over the elastic strap 17. After the foot and leg have been inserted into place, the rear portion of the side piece 6 is doubled back or folded, as indicated in Figures 3 and 4, to cause the protector to be contracted and to conform substantially to the parts that are to be protected. The pairs of straps 14, 15 and 16 are then tied together to prevent unfolding of the folded portion and to hold the protector in place. When the protector is in its operative position, it operates to prevent the ankle portion of the wearer's stocking from being soiled by mud or water that may be splashed by passing pedestrians or vehicles. As previously pointed out, the stay or stiffened member 18 serves to prevent the protector from collapsing and to prevent wrinkling of the rubberized silk material. To remove the protector it is only necessary to untie the straps 14, 15 and 16. This releases the folded portion and permits the protector to be expanded into its normal or inoperative position, in which position said protector is free to be slid off the foot and shoe.

The protector consists of but a small number of parts and may be produced at a low and reasonable cost. Because it is formed of inelastic material, the protector does not interfere with or stop the circulation of blood in the wearer's leg.

The invention is not to be understood as restricted to the details set forth, since these may be modified within the scope of the appended claim, without departing from the spirit and scope of the invention.

Having thus described the invention, what I claim as new and desire to secure by Letters Patent, is:

As a new article of manufacture, a stocking 125 ing protector comprising a pair of separately formed inelastic waterproof side pieces adapted to fit against the sides of the wearer's ankle, having the side margins thereof stitched together to form a circumferentially continuous tubular member and so formed 130

that the member is comparatively short and adapted to extend over the instep of the wearer and to encircle the ankle beneath the calf of the wearer's leg, one of said side pieces 5 being wider than the other, the member being of sufficient width to permit it to be slipped readily over the foot and shoe, said one side piece being adapted to be folded or doubled back, after the protector has been slipped into 10 place, to cause the member to fit closely and correspond substantially to the contour of the ankle, and pairs of straps for holding the folded part in place and thereby retaining the protector in its operative position, the 15 straps of each pair being anchored by the stitching at the side margins of the pieces and arranged so that when they are tied together they extend across said folded part.

Signed at Chicago, Illinois, this 27th day
20 of February, 1929.

ANNA L. CROCKER.
